Albert E. Hotchkiss
Inventor
By Atty
Earle Seymour,

UNITED STATES PATENT OFFICE.

ALBERT E. HOTCHKISS, OF WALLINGFORD, CONNECTICUT.

THILL-COUPING.

SPECIFICATION forming part of Letters Patent No. 509,165, dated November 21, 1893.

Application filed June 12, 1893. Serial No. 477,332. (No model.)

To all whom it may concern:

Be it known that I, ALBERT E. HOTCHKISS, of Wallingford, in the county of New Haven and State of Connecticut, have invented a new 5 Improvement in Antirattlers for Thill-Couplings; and I do hereby declare the following, when taken in connection with accompanying drawings and the letters of reference marked thereon, to be a full, clear, and exact 10 description of the same, and which said drawings constitute part of this specification, and 15 represent, in—

Figure 1, a side view of a thill coupling, showing the anti-rattling device in position; 20 Fig. 2, a top view of the same; Fig. 3, a vertical central section; Fig. 4, a face view of the plate of the anti-rattling device.

This invention relates to an improved anti-rattling device for thill couplings, the object being to produce a simple and cheap device which may be readily applied to thill couplings, and the invention consists in the construction hereinafter described and particularly recited in the claims.

25 As herein shown, the anti-rattling device is applied to a coupling of ordinary construction, consisting of a clip A, adapted to be applied to an axle B, the lower ends of the clip passing through a plate C below the axle, 30 where they are secured by nuts D. From the forward side of the clip, arms E E extend, between which the thill-eye is held by a bolt G. The anti-rattling device consists of a longitudinally bowed plate H, preferably formed 35 from cast metal and constructed with ears I I, at its upper end. The upper edge between the ears is thicker than the body portion of the plate and is constructed with a recess J. Within this recess is a stud K. The lower 40 end of the plate is constructed with an internally screw threaded perforation adapted to receive a screw L.

M is a spring corresponding in width to the width of the plate H, and is constructed at

its upper end with an opening N, corresponding in size to the stud K, over which it is placed, the upper end of the spring resting within the recess J, which protects its upper edge, and prevents turning.

To apply the anti-rattling device, the screw 50 L is withdrawn, and the spring placed in position on the plate H, and the plate and spring inserted between the clip and the thill-eye, and forced downward until the shoulders I I, of the plate rest on the top of the arms E E. 55 The screw is then inserted through the plate H and turned against the spring N, forcing the spring outward against the thill-eye, thereby forcing the thill-eye against its bolt G.

If desired a jam nut O, may be applied to 60 the screw L to prevent any possible accidental displacement.

I claim—

1. The herein described anti-rattling device for thill couplings, consisting of a curved 65 plate constructed with arms at its upper end, a spring, removably secured to the front face of the said plate at its upper end, and a screw adapted to force the lower end of the spring from the said plate, substantially as described. 70

2. The herein described anti-rattling device for thill couplings, consisting of a plate constructed at its upper end with laterally projecting ears and a forwardly projecting stud, a spring constructed at one end with an 75 opening which receives the said stud, and a screw passing through the lower end of the said plate, and impinging against the spring, substantially as described, and whereby by turning the screw the spring may be forced 80 away from the plate.

In testimony whereof I have signed this specification in the presence of two subscribing witnesses.

ALBERT E. HOTCHKISS.

Witnesses:

S. E. HOTCHKISS,

A. S. HOTCHKISS.
